UNITED STATES PATENT OFFICE.

JOSEPH R. PALMENBERG, OF NEW YORK, N. Y.

DESIGN FOR A HAT AND COAT RACK.

SPECIFICATION forming part of Design No. 12,625, dated December 20, 1881.

Application filed October 20, 1881. Term of patent 14 years.

To all whom it may concern:

Be it known that I, JOSEPH R. PALMENBERG, of the city of New York, county and State of New York, have invented a new and original

5 Design for a Hat and Coat Rack, of which the following specification is a full, clear, and exact description, reference being had to the accompanying drawing, forming part of this specification.

10 The drawing represents a perspective view of my newly-designed hat and coat rack.

My newly - designed hat and coat rack consists of a disk-shaped block, *a*, having an arm, *b*, for attachment to a wall or other support.

15 To this block are secured upwardly-projecting curved rods *c*. *d d* are pins projecting from the circumference, and *e e* pins projecting from the lower side, of the disk *a*. *f f* are cone-shaped ornaments attached to the two flat sides 20 of said disk. The disk *a* is preferably corrugated at its circumference.

I claim as my invention—

1. The design for a hat and coat rack, consisting of the disk-shaped block *a* and curved rods *c c*, substantially as shown.

2. The design for a hat and coat rack, consisting of the block *a*, rods *c c*, and arm *b*, substantially as shown.

25 3. The design for a hat and coat rack, consisting of the block *a*, rods *c c*, arm *b*, and pins *d d*, substantially as shown.

4. The design for a hat and coat rack, consisting of block *a*, rods *c c*, arm *b*, pins *d d*, and cone-shaped ornaments *f f*, substantially as shown.

J. R. PALMENBERG.
